UNITED STATES PATENT OFFICE.

HENRY HILL, OF NOTTINGHAM, ENGLAND.

CIRCULAR-WARP MACHINE.

SPECIFICATION forming part of Letters Patent No. 667,701, dated February 12, 1901.

Application filed December 30, 1897. Serial No. 664,586. (No model.)

To all whom it may concern:

Be it known that I, HENRY HILL, a subject of the Queen of England, residing at Nottingham, England, have invented certain new and 5 useful Improvements in Circular-Warp Machines, (for which I have obtained Letters Patent in Austria, No. 47/2,939, dated May 25, 1897,) of which the following is a specification.

This invention relates to improvements in 10 circular-warp machines for producing seamless tubular-warp lace fabrics—such, for example, as foundations for incandescent mantles.

The invention will be best understood by 15 reference to the accompanying drawings, in which—

Figure 1 is a front elevation showing the principal part of a machine constructed according to my invention. Fig. 2 is a vertical 20 section, drawn to a larger scale, of part of the machine.

Like letters indicate like parts throughout the drawings.

The needles D (see Fig. 2) are arranged in 25 a circumferential line, with their length parallel to the axis of the machine, as shown, or nearly so. They are secured to one common needle cylinder or sleeve D', which is mounted loosely on a hollow cylindrical casing D², 30 which latter is preferably arranged with its axis vertical, as shown, and is secured in a boss or seat B² in the cross-stay B of the framing. The needles D are also supported in a circular slay D⁴, secured to the upper end of 35 the casing D².

The needle-cylinder D' (see Fig. 1) is reciprocated vertically on the casing D² by one or more cams on a main shaft which is placed below the needle-cylinder and is not shown. 40 The movement of this cam or these cams is communicated to the needle-cylinder by a lever and a forked connecting-rod jointed to the lugs D³ of the needle-cylinder. If preferred, an eccentric or crank may be employed instead of the cams.

The whole of the needles D are raised and lowered simultaneously, and the fabric G (see Fig. 2) as it is produced is carried down the interior of the cylindrical casing D² to a take-up roller, from which it may be delivered onto a work-roller in a well-known manner.

The thread-guides, which supply the threads

to the needles, are dependent and may be formed of spring-wire. They are subdivided into two sets—an inner set I and an outer set I'—both arranged in concentric circumferential lines, one set being within the other. Those in the inner set I are cranked outward at their lower ends, while those in the outer set I' are cranked inward, so that the eyes at 60 their lower ends, through which the threads I² pass, are brought together, as shown. The inner set I is arranged around a cylindrical casing or sleeve j, and their upper ends are secured to a raised rib or flange J' at the upper end of the said casing. The cylindrical casing J is mounted on the lower end of a hollow shaft J², which latter is mounted in a sleeve-bearing J³, secured to or formed on a cross-stay J⁴. The outer set I' is arranged 70 around a cylindrical casing K, surrounding the inner set of needles, and their upper ends are secured to a raised rib or flange K' at the upper end of the said casing in the same manner as the inner set. The casing K is provided with an extended flange K², which fits loosely in a seating K³, formed in the cross-stay J⁴, and is held in this seating by a ring K⁵, secured to the seating K³. The ends of the cross-stays J⁴ and K⁴ (see Fig. 1) are connected to bracket-bearings K⁶ K⁷, mounted 75 on the pillars C C', respectively.

The lower cranked parts of the two dependent sets of thread-guides I I' (see Fig. 2) are held by their own elasticity normally on the 85 surfaces of the corresponding cylinders J and K; but the said ends are opened out into the positions shown in dotted lines by collars or rings J⁸ K⁸, mounted on and sliding on the casings J and K, respectively. As these collars or rings J⁸ and K⁸ are moved from the position shown at the top of their corresponding casings J and K to the position shown in dotted lines at the bottom of said casings the lower ends of the whole of the thread-guides 95 I I' will be forced outward radially into the position shown in dotted lines, and they will again return to their normal position when the collars or rings J⁸ K⁸ are raised again. In addition to imparting a radial motion to the 100 guides I I' the rings J⁸ K⁸ are provided with slay-rings J⁹ K⁹, respectively, and these slay-rings are provided with recesses in their peripheries to receive the guides, and the latter

are thus by this means held in their relative positions.

Vertical reciprocating movement may be imparted to the two collars J⁵ K⁸ by the following arrangement: The collar or ring J⁵ (see Fig. 2) is connected by two bars L, working in slots or recesses in the cylindrical casing J, to a ring L', which is held loosely and may thus rotate in a seating in a ring L² by means of a ring L³, secured to the ring L², as shown. The ring L² (see Fig. 1) is mounted on the sleeve-bearing J⁸ and is connected by adjustable rods L⁴ to a cross-head M. The collar or ring K⁸ (see Fig. 2) is connected to the cross-head M by a similar arrangement. The collar or ring K⁸ is connected by two bars N, working in slots or recesses in the casing K, to a ring N', which is held loosely in a seating in a ring N² by a ring N³, secured to the ring N², as shown. The ring N² is connected by adjustable rods N⁴ to the cross-head M. The cross-head M (see Fig. 1) is mounted on the upper ends of two shafts M', which are carried in the bracket-bearings K⁶ K⁷. The lower ends of the two shafts M' are connected by connecting-rods M² to two levers provided with antifriction-rollers which are in peripheral contact with cams on the main shaft, hereinbefore referred to. In addition to their radial movement the thread-guides are reciprocated angularly. This is effected by rotating the cylindrical casings J and K, to which the guides are secured, and the mechanism immediately connected therewith bodily. The cylindrical casing J, which is secured to the hollow shaft J², is reciprocated angularly by an arm O, (see Fig. 1,) secured to the latter. This arm O engages with the inner end O' of a lever O², mounted on the pillar C, and the outer end O³ of the lever O² engages with and is actuated by a pattern-wheel O⁴, secured to a vertical shaft, which is connected to the main shaft by suitable gearing. The casing K, which is reciprocated in its seating K³, is provided with an arm Q, which engages with the inner end Q' of the second lever Q², mounted on the pillar C. The outer end Q³ of the lever engages with a second pattern-wheel Q⁴ on the vertical shaft. The threads I² are carried from a warp beam or spool, which may be placed above the machine, through the space between the two cylindrical casings J and K, to the eyes in the lower ends of the thread-guides I I', and thence to the needles D.

The operation of the machine is as follows: The needles D rise until their upper ends are above the lower ends of the guides I I' while the latter are in their normal position, as shown. The lower ends of the guides I I' are then moved radially outward into the position shown in dotted lines in Fig. 2, passing and carrying the threads between the needles. The guides are then moved angularly one or more needles, both sets in the same direction or the set I in the reverse direction to the set I', and return through the needles to their

normal position again, thus lapping the threads on the needles. The needles are then lowered to draw the loops through the preceding loops and the above process again repeated. It will be understood that in order to form a continuous fabric the thread-guides must be moved angularly more than one needle either every course or at intervals of every two or more courses, which is determined by the character of the fabric which is being produced. The work is held down by a circular plate T, (see Fig. 2,) placed within the line of the needles. This plate is connected to the lower end of a spindle T', placed within the hollow shaft J². It is normally held down by a spring T², (see Fig. 1,) but is raised each course by the cross-head M engaging with a striking part or pin T³ in the spindle T'. The mesh of the work may be changed by shogging the vertical shaft which carries the pattern-wheels O⁴ Q⁴ longitudinally, so as to throw the pattern-wheels O⁴ Q⁴ out of action or bring other pattern-wheels into engagement with the ends O³ Q³ of the levers O² Q². The vertical shaft P may be shogged by any well-known arrangement controlled by the attendant or by a pattern-chain or other convenient arrangement.

The latches of the needles D are prevented from rebounding onto the hooks when the loops have passed over and relieved them by a circular ring or plate V, which is connected by brackets V' to the cross-stay K⁴.

I claim—

1. In a circular-warp machine, the combination with the needles, of a set of dependent elastic guides provided with warp-eyes at their lower ends for the passage of the warp-threads, a cylindrical casing which may be reciprocated angularly and around which the warp-guides are secured, and a collar arranged to slide up and down on the cylindrical casing for moving the lower ends of the guides radially outward, said guides being returned to normal position by their own elasticity when released by the collar; substantially as described.

2. In a circular-warp machine, the combination with the needles, of a set of dependent elastic guides provided at their lower ends with warp-eyes for the passage of the warp-threads, a cylindrical casing which may be reciprocated angularly and around which the warp-guides are secured, means for reciprocating the casing, a collar arranged to slide up and down on the cylindrical casing for moving the lower ends radially outward, said guides returning automatically to normal position when released by the collar, and means for operating the collar; substantially as described.

3. In a circular-warp machine, the combination with the needles of dependent warp-guides provided at their lower ends with warp-eyes for the passage of the warp-threads, a cylindrical casing which may be reciprocated angularly and around which said guides are

secured, means for reciprocating the casing, a collar sliding up and down on the cylindrical casing, a rotatable ring connected to the said collar, a seating-ring for the rotatable ring, a cross-head connected to the seating ring, and means for reciprocating the cross-head; substantially as described.

4. In a circular-warp machine, the combination with the needles, of an inner and outer set of dependent warp-guides provided at their lower ends with warp-eyes for the passage of the warp-threads, a cylindrical casing mounted on the central shaft around which the inner guides are secured, a second outer concentric cylindrical casing around which the outer guides are secured, a seating in which said cylinder is mounted, means for reciprocating both the said casings angularly, a collar sliding up and down on each cylindrical casing for moving the lower ends of the guides

outward, and means for operating both collars; substantially as described.

5. In a circular-warp machine, the combination of the needles, of an inner and outer set of dependent warp-guides formed of 25 spring-wire, arranged in concentric circumferential lines, one within the other, the inner set being cranked outward at their lower ends, and the outer set being cranked inward, whereby the eyes formed in these lower 30 ends through which the threads pass, will be brought together and means for actuating said guides; substantially as described.

In testimony whereof I have hereto set my hand in the presence of the two subscribing 35 witnesses.

HENRY HILL.
